ORNAMENTALLY COLORING PAPER

Ethan F. Bassford, Nutley, N. J., assignor to
 George La Monte & Son, Nutley, N. J., a corporation of New Jersey

Application September 23, 1937, Serial No. 165,237

5 Claims. (Cl. 8—7)

This invention relates to ornamentally coloring paper and method of making such paper. This invention relates especially to the production of paper containing portions colored to different degrees of color intensity so as to give the effect of shading adjacent lettering, marks, or other legends appearing on the paper.

Heretofore check paper or the like has been made by applying a bath of liquid coloring material such as a dye dissolved in a suitable solvent to paper and then passing the paper between rolls which apply high pressure to certain portions only of the paper. The paper is then passed through a wringer. The result of this operation is to afford a paper having two degrees of color intensity. Where the paper was subjected to pressure during the rolling step the intensity of the color is somewhat deeper than where the pressure was not applied. In this manner paper, such as check paper, having alternate light and dark lines, for example, can be produced.

According to the present invention, paper can be produced which contains portions which are of predetermined form and which are usually in the form of legends, such as printing, ornamental designs and the like that are different in color intensity from a background portion of the paper; and in addition, an attractive shaded effect of a still further color intensity is produced adjacent the portions of predetermined form, as will be described more in detail below.

As illustrative of this invention, paper is subjected to locally applied pressure so as to have portions of the surface thereof of substantially different absorptiveness for a liquid coloring material. A portion or plurality of portions of lesser absorptiveness is preferably of predetermined form such as lettering, ornamental designs, and the like. And it is a feature of this invention that a shaded effect is produced in local areas adjacent the portions of lesser absorptiveness by successive applications of liquid coloring material. One application of the liquid coloring material is made to the portion of the paper having greater absorptiveness not only in the local area to constitute the shading adjacent the portion of lesser absorptiveness, but also beyond such area, and another application of the liquid coloring material is made to the portion of the surface of the paper having greater absorptiveness, but only in the area to be shaded and which is adjacent to the portion of lesser absorptiveness. Preferably this is done by spreading or wiping free liquid coloring material overlying the portions of lesser absorptiveness onto the local areas

adjacent said portions which are to be shaded. In this manner, the local areas referred to have imparted to them a greater color intensity than the color intensity of the other portions of the paper which have the greater absorptiveness for coloring material. The portions of the paper having the lesser degrees of absorptiveness for the coloring material are colored least of all. Features of this invention relate both to the method of producing such paper and the resultant product.

Paper produced according to this invention has a very attractive appearance, and while it is suitable for a variety of purposes, it may be used to advantage as a fancy wrapping paper. In such case, for example, wrapping paper can be produced which contains at intervals about the surface thereof some legend such as a trade-mark including lettering and/or an ornamental design. Adjacent the legend portions there is shading which is of a substantially deeper color than the balance of the background. This shading greatly enhances the ornamental character of the paper and makes the legends appear to stand out in a very pronounced and pleasing manner from the portion of the paper constituting the background therefor.

Further purposes, features and advantages of this invention will be apparent from the following description of the accompanying drawing which illustrates certain embodiments of this invention, wherein

Figure 1 is a side view, largely diagrammatic, of apparatus which may be used in the practice of this invention;

Figure 2 is a side view, largely diagrammatic, of an alternate form of apparatus which may be used according to this invention;

Figure 3 is a plan view of a portion of a sheet of paper embodying this invention and produced according to this invention with a corner of the paper turned to show the opposite surface thereof; and

Figure 4 is a view similar to that in Figure 3 of an alternate form of paper embodying this invention and produced according to this invention.

The production of paper according to this invention may be illustrated in connection with Figure 1. A sheet 10 of paper is passed over a guide roll 11 and is immersed by means of roller 12 in a bath of coloring material 13 such as a solution of a suitable dye, the coloring material being contained in a tank 14 or other suitable container. As the sheet 10 of paper is removed

from the bath of coloring material 13, it carries an excess of the liquid coloring material on the surface thereof. The paper then passes between squeeze rolls 15 and 16. In the illustrated embodiment shown in Fig. 1, the roll 15 has a smooth surface. The roll 16 has recesses 17 in the surface thereof. In this manner pressure is not applied to the paper throughout the entire extent thereof but is applied to only certain portions thereof. The portions of the paper which are compressed are modified as to the absorptiveness thereof for the coloring material, the paper being rendered more absorptive at the points where the pressure is applied. The degree to which the absorptiveness of the paper is effected depends upon the pressure which is used. The greater the amount of pressure, the more the paper is modified to increase its absorptiveness for the liquid coloring material. Pressures upwards of 150 pounds per inch of line contact between the rolls have been found to be especially satisfactory in the practice of this invention, although there is a wide latitude with regard to the degree of pressure which may be used.

Where the pressure is applied to the paper, any excess of the liquid coloring material is removed from the paper. The excess of liquid coloring material is not removed, however, from the portions of the paper which have not been subjected to pressure and which register with the recesses 17 in roller 16. Therefore, as the paper emerges from the rolling step, it carries free liquid coloring material overlying the portions of the paper which have not been compressed, and which have the lesser degree of absorptiveness for the coloring material. After the paper has emerged from the rolling step the paper passes the spreader 18 which may be in the form of a bar, brush, roller, or the like. The spreader wipes the free liquid coloring material which overlies the portions of the sheet having the lesser absorptiveness for the liquid coloring material, onto local areas of the portion of the sheet having a greater absorptiveness for the coloring material, with the result that these local areas of the portion of the sheet having the greater absorptiveness for the coloring material receive a second application of the coloring material. Where this second application is made to the portion of the sheet having the greater absorptiveness for the coloring material, a greater degree of coloration is afforded than in the remainder of the portion of the sheet having the greater absorptiveness for the coloring material.

While the liquid coloring material has remained in contact with the portions of the sheet having the lesser degree of absorptiveness for the coloring material, the relatively lesser absorptiveness of such portions prevents the coloring material from being absorbed thereby to the extent to which the coloring material is absorbed by the portions of the sheet having greater absorptiveness for the coloring material.

After passing from the spreader 18 the sheet is passed through wringer rolls 19 which squeeze the paper to remove excess liquid before the paper is passed to drying rolls 20. After the paper has dried, the usual finishing operations such as calendering, trimming, wrapping, etc. may take place. If the spreader 18 is omitted the wringer rolls will have a somewhat analogous spreading effect, but the use of a separate spreader spaced from the wringer rolls is preferred.

The finished product is illustrated in connec-

tion with Fig. 3, for example. The recesses 17 in the roll 16 are in the form of a legend 21, for example, the term "legend" being regarded as applicable to lettering, trade-marks, ornamental designs, or other marks. The paper after having passed through the bath of coloring material 13 and between the rolls 15 and 16, becomes colored so as to form a background for the legend 21, this background portion 22 being indicated by light stippling. The coloring material 10 is absorbed in this portion to a greater degree than in the legend 21 due to the fact that the absorptiveness of the paper has been increased by the application of pressure to the portion 22. The paper in passing under the spreader 18 has 15 the free liquid coloring material overlying the legends 21 wiped from the legends 21 into local areas 23 on the side of the legends 21 which is contrary to the motion of the paper through the apparatus, and the coloring material is absorbed in such areas so as to color them to a greater degree of intensity than the background 22, as indicated by the heavy stippling. The legends 21 which are colored the least are thereby set off from the background 22 by the shaded areas 23 to afford the pleasing and ornamental effect 20 which is shown in Fig. 3.

Other ornamental effects can be produced such as that illustrated in connection with Fig. 4. In the production of such paper the recesses 17 in roll 16 are caused to surround the legend 24 so that the legend portion 24 may be in a dark color and set off against a contrasting lighter color. The portions 25 of the paper which register with the recesses 17 have a lesser degree of absorptiveness for the liquid coloring material than the remainder of the paper to which pressure is applied including the legend 24. The body portion or background 26 of the paper is colored as described in connection with Fig. 3. The legend 24 and the shaded area 27 become colored more intensely than the background 26 when the paper passes underneath the spreader 18, the free coloring material overlying the portion 25 being wiped onto the legend portion 24 and likewise to one side of the area 25 so as to produce the shaded portion 27. The letters and figures constituting the legend portion 24 are colored to approximately the same degree of intensity as the shaded area 27.

The shaded areas produced according to this invention may be caused to lie in any desired relative direction with respect to the legend portions on the paper. For example, the shading may be diagonally disposed with respect to the legend portions, as illustrated in Fig. 3, or may be disposed to one side of the legend portions, as illustrated in Fig. 4. This can be controlled by locating the recesses 17 in the roll 16 which determine the form of the legend portion with reference to the position of the spreader 18 and the motion of the paper. By disposing the spreader in a different relation to the motion of the paper or by moving the spreader, other types and directions of shading can be produced as may be desired.

In the foregoing operation both sides of the paper are colored and a shading effect is produced on one side only of the paper. A shading 70 effect could be produced on both sides of the paper by having recesses such as recesses 17 in roll 15 as well as in roll 16 and using spreaders on both sides of the paper. If only one side of the paper is to be colored, the coloring material

can be applied on only one surface of the sheet of paper in practicing this invention.

An alternate form of apparatus and method for producing ornamenteally colored paper according to this invention shown in connection with Fig. 2 which is similar to the apparatus shown in Fig. 1, except with reference to the character of the spreader and the inclusion of means for making a second application of coloring material to the back of the paper. Where the parts shown in Fig. 2 are similar to the parts shown in Fig. 1, they are indicated by like reference characters, and repetition of the description thereof will not be repeated. In Fig. 2 the paper sheet 10 after having been subjected to compression between rolls 15 and 16 is passed underneath the roller 28 which is partially immersed in the bath 13 of coloring material. The sheet 10 then passes between the wringer rolls 19, as described in connection with Fig. 1. In this manner, the coloring material can be applied only to the back of the paper inasmuch as the roller 28 is not immersed sufficiently in the bath of coloring material to permit contact of the coloring material with the upper surface of the sheet 10. In this manner the back of the paper can be colored to any desired degree and one or more rollers such as roller 28 may be used for this purpose. The effect produced by the second application of coloring material to the back of the paper is indicated in Fig. 3. In this figure a corner 29 of the paper is shown turned backwardly so as to exhibit the back of the paper. As indicated by the heavy stippling on the back of the paper, the back of the paper is colored relatively heavily and the intensity of the color on the back of the paper may correspond, for example, with the intensity of the color in the shaded areas 23 hereinabove described in connection with Fig. 3. Paper of the character shown in Fig. 3 is to be contrasted with paper of the character shown in Fig. 4 in which the turned back corner 30 has not received a second application of coloring material on the back thereof. In Fig. 4 the back of the paper, as indicated by the light stippling, corresponds in color intensity to the background portion 26 of the face of the paper.

In using the apparatus shown in Fig. 2, the roller 28 acts as a spreader for wiping free coloring material deposited on the face of the paper by recesses 17 in the roll 16 to one side of the portions of the paper having lesser absorptiveness for coloring material in the same manner that the spreader 18 in Fig. 1 accomplishes this purpose. If desired, the roller 28 may be held stationary in order to augment the spreading effect produced thereby. An overall application of coloring material to the face of the paper to be shaded by the spreader should be avoided after the paper emerges from the rolls 15 and 16 in producing a shaded effect of the character described above.

The character of shading that is produced according to this invention may be controlled by adjusting the speed of the paper, the depth of the recesses 17 in roller 16 and the viscosity of the liquid coloring material. The intensity of color that is imparted to any one portion of the paper is effected by the length of time that the liquid coloring material is maintained in excess in contact therewith inasmuch as by increasing the length of such contact a greater amount of the coloring material will be absorbed. By increasing the depth of the recesses 17 in the roll 16, increased amounts of free coloring material

can be deposited on the surface of the paper. In this manner, the extent and intensity of color of the shaded areas can be increased. By varying the viscosity of the liquid coloring material, the extent of the shaded areas and the amount of coloring material absorbed by the shaded areas can be varied. It is thus apparent that by using a dye bath of one concentration, ornamenteally colored paper containing portions having at least three degrees of color intensity can be produced in a single passage of the paper through the apparatus, and that the character of the shading can be varied as may be desired.

The foregoing is regarded as the preferred practice of this invention. However, ornamenteal color effects may be produced according to this invention, utilizing other methods of procedure. For example, whenever the paper is subjected to pressure so that areas of different absorptiveness are produced, the coloring material may be applied in any suitable way or sequence to the portions of greater absorptiveness adjoining the portions of lesser absorptiveness so as to apply the coloring material to limited areas adjoining the portions of lesser absorptiveness for a time more prolonged than the time the coloring material is applied to the balance of the portion of greater absorptiveness thereby producing greater color intensity in said areas than in the remainder of the portion of greater absorptiveness. In such case the portions of lesser absorptiveness are colored least of all.

Instead of using pressure rolls which are regarded as preferable, to apply pressure to a limited portion or to limited portions of a sheet of paper, a stamp press or the like may be used for producing areas of a sheet of paper having different degrees of absorptiveness for coloring material. In any such case liquid coloring material may be applied to the paper and will be absorbed in different degrees by the portions having different degrees of absorptiveness, the liquid coloring material being applied to limited areas of the portion of the paper having the greater absorptiveness for the coloring material for a greater length of time than to the remainder of the portion of greater absorptiveness to produce a shaded effect of the character herein described.

Any suitable liquid coloring material can be used. For example, coloring materials such as water-soluble dyes, spirit-soluble dyes, dispersed colloidal dyes, finely-divided pigments and the like of which many are well-known, may be used.

While this invention has been described in connection with certain specific embodiments thereof, it is to be understood that this has been done merely for the purpose of affording examples of the practice of this invention and that the scope of this invention is to be limited only by the language of the following claims.

What I claim is:

1. A method of making ornamenteally colored paper which comprises making paper having portions of a surface thereof of substantially differing absorptiveness for a liquid colored material, portions of lesser absorptiveness being of predetermined form, and producing a shaded effect in local areas adjoining said portions of lesser absorptiveness by successive applications of the coloring material, one application of the coloring material being an all-over application thereof to said surface of the paper, and another application of the colored material being made by spreading free coloring material from portions overlying said portions of lesser absorptiveness

onto said adjoining local areas of said surface having greater absorptiveness.

2. A method of making ornamenteally colored paper which comprises making paper having portions of a surface thereof of substantially differing absorptiveness for a liquid coloring material by compressing a portion only of the paper to impart greater absorptiveness to such portion leaving portions of lesser absorptiveness which are of predetermined form, and producing a shaded effect in local areas adjoining the portions of lesser absorptiveness by applying the coloring material both to said portions of lesser absorptiveness and to said portion of greater absorptiveness, said latter portion including said areas and extending beyond said areas, a substantial amount of free coloring material being left overlying said portions of lesser absorptiveness, and then spreading said free coloring material from said portions of lesser absorptiveness into said local areas of greater absorptiveness which adjoin said portions of lesser absorptiveness thereby producing at least three degrees of intensity of color on said sheet of paper, the portions having the lesser absorptiveness for the coloring material being colored the least, the local areas adjoining said portions having the lesser absorptiveness being colored the most, and the remainder of the paper which has the greater absorptiveness being colored to a degree intermediate the color of said local areas and the color of said portions of lesser absorptiveness.
3. A method of making ornamenteally colored paper which comprises making paper having portions of a surface thereof of substantially differing absorptiveness for liquid coloring material by passing the paper between rolls at least one of which is adapted to apply pressure to certain portions of the paper to increase the absorptiveness of said portions for a coloring material leaving other portions of lesser absorptiveness for the coloring material, and producing a shaded effect in areas adjoining said portions of lesser absorptiveness by depositing said coloring material during said rolling step so as to overlie said portions of lesser absorptiveness, wiping said free coloring material onto said local areas of greater absorptiveness and making another application of said coloring material to said portions of greater absorptiveness including said areas and extending beyond said areas.
4. A method of making ornamenteally colored paper which comprises applying a liquid coloring material to a surface of a sheet of paper so

as to leave an excess of said coloring material on said surface, rolling said sheet with a roller adapted to exert pressure on certain portions only of said sheet thereby increasing the absorptiveness for the coloring material of the portions of the sheet to which the pressure is applied and removing excess coloring material from said portions, a substantial amount of free coloring material being left overlying the portions of said sheet to which said pressure is not applied, which latter portions are of predetermined form and have lesser absorptiveness for the coloring material than the portions of the sheet to which pressure has been applied, and after the rolling step wiping the free coloring material overlying the said portions of lesser absorptiveness onto local areas adjoining and to one side of said portions of lesser absorptiveness so as to make a second application of said coloring material to said areas and thereby color said areas to a greater intensity than the portions of greater absorptiveness of said sheet to which said second application is not applied.

5. A method of making ornamenteally colored paper which comprises applying a liquid coloring material to both sides of a sheet of paper leaving an excess of said coloring material on at least one surface of said sheet, rolling said sheet with a roller adapted to exert pressure on certain portions only of said surface of said sheet thereby increasing the absorptiveness for the coloring material of the portions of the sheet to which the pressure is applied and removing excess coloring material from said portions, a substantial amount of free coloring material being left overlying the portions of said surface of said sheet to which the pressure is not applied, which latter portions are in predetermined form and have lesser absorptiveness for the coloring material than the portions of the sheet to which pressure has been applied, and after the rolling step wiping the free coloring material overlying the said portions of lesser absorptiveness onto local areas adjoining and to one side of said portions of lesser absorptiveness so as to make a second application of said coloring material to said areas and thereby color said areas to a greater intensity than the portions of greater absorptiveness of said sheet to which said second application is not applied, the opposite surface of said sheet only receiving a further application of said coloring material uniformly throughout after said rolling step.

ETHAN F. BASSFORD.
